UNITED STATES PATENT OFFICE.

CLARENCE C. BAKER, OF ALAMEDA, AND EARL A. CHANDLER, OF SAN FRANCISCO,
CALIFORNIA.

CHANGEABLE SIGN.

1,251,733.

Specification of Letters Patent.

Patented Jan. 1, 1918.

Application filed September 30, 1916. Serial No. 123,034.

To all whom it may concern:

Be it known that we, CLARENCE C. BAKER and EARL A. CHANDLER, citizens of the United States, residing, respectively, at Alameda, in the county of Alameda and State of California, and San Francisco, in the county of San Francisco and State of California, have invented new and useful Improvements in Changeable Signs, of which the following is a specification.

The object of the present invention is to provide a device for exhibiting signs, and especially for indicating characters denoting the tare weights of railroad cars, which shall be simple and cheap in construction, compact in form, and can be easily changed to exhibit different signs as desired.

In the accompanying drawing, Figure 1 is a front view of our improved tare weight indicator; Fig. 2 is a rear view thereof; Fig. 3 is a sectional view on the line 3—3 of Fig. 2; Fig. 4 is a similar view, the parts of the indicator being extended; Fig. 5 is a section on the line 5—5 of Fig. 3; Fig. 6 is a section on the line 6—6 of Fig. 4; Fig. 7 is an enlarged broken detail view of a sign card; Fig. 8 is a sectional view on the line 8—8 of Fig. 7.

Referring to the drawing, 1 indicates a board forming part of the side of a car, to which is secured, by screws 2, a rectangular plate or frame 3, having flanged portions 4, the edges of which rest against the board 1. From standards 6 projecting from the face of the plate near the ends of its lower edge extend at right angles studs 7, on which are pivoted arms 8, the outer portions 9 of which are of reduced width. Near the outer ends of said outer portions 9 and of the inner portions of the arms are secured to said arms cross bars 11, which are semi-circular in cross section through almost their entire length and to which are secured, by screws 12, cross bars 13 which are also semi-circular in cross section, so that the two parts when placed together form a round compound bar. Each of these bars 11, 13 has secured thereto, or formed integral therewith, semi-circular plates or disks 14 having flanges 15, so that the bars when placed together have thereon round flanged rings or disks. By means of said flanges 15 there are supported upon the several disks sheets 17 of metal or other suitable material, each sheet being crimped at the top, as shown at 18, for

greater strength and having, near the top edge, rectangular recesses 19 opening through said top edge by narrow openings 21. The openings 21 are of just sufficient width to permit the disks, but not the flanges, to pass therethrough, while the recesses are of sufficient width to permit the flanges to pass therethrough.

The sheets are placed in position engaging the flanges 15 of the plates 14 of the bar 11, and then the bar 13 is secured to the bar 11 so that the metal sheets can revolve on said flanges throughout their whole circumference. Each of the upper groups of sheets displays only the numerals 0 to 9, as shown at 23, but the right-hand of the lower groups of sheets displays characters 24 indicating the month and year when the car was weighed and the left-hand groups each display the letters of the alphabet, as shown at 25, indicating by its initial or terminal letters the place where the car was last weighed. There are therefore many more sheets in the lower groups than in the upper. For this reason the lower disks are of greater diameter than the upper disks and the lower portion of the plate 3 is recessed or closer to the board 1 than the upper portion. The plate is formed with holes 26 to receive said disks.

Pivoted on the studs 7, outside the arms 8, are the lower ends of arms 27, the upper ends of which are pivotally connected, as shown at 28, to the sides or flanges of a cover 29, which incloses the sheets and plate 3. Said cover 29 is formed with rectangular holes 31 through which the characters 23, 24, 25 are exhibited and is pressed out, as shown at 32, to receive the disks.

The cover is held in position close to the signs by means of upper and lower latches 33, 34, which engage lips 35, 36 extending inwardly from the flanges of the cover. The lower latch 34 has a stem 37 which slides in a guideway 38 secured to the back of the plate 3 and is pressed outwardly by a coiled spring 39 within said guideway and compressed between the inner ends of the stem and guideway. To said latch 34 is secured a rod 41 pivoted, as shown at 42, to an arm of a lever 43, pivoted, as shown at 44, on the back of the plate 3, the other arm of said lever being connected rigidly to a stem 46 of the latch 33.

To remove the cover a sufficiently long instrument, as a chisel, tapered to a blunt

end is inserted between the lower flange 29 and the board 1 and the outer end of the instrument is pressed toward the side of the car, so that the inner end is raised, the thick 5 portion of the instrument serving as a fulcrum. The movement of the lip 36 against the beveled face of the latch forces the latch inward, and also forces the latch 33 upward. This action frees the lip 36 from the latch 10 34, so that the cover is free both at top and bottom and can be raised so as to permit of free access to the sheets 17 to revolve the same upon the disks, and to change the character of the sign exhibited.

15 Secured upon the upper flange 4 of the plate 3 is a cylindrical casing 50 in which is received a stem 51, upon which is wound a sheet of paper or the like material, upon which is marked other information in regard 20 to the car.

We claim:—

1. In a device of the character described, the combination of a plate provided with means for securing it to a board or the like, 25 arms pivoted to swing to and from said plate, cross bars carried by said arms, rings carried by said cross bars, sheets exhibiting characters revoluble on said rings, a cover for said sheets having openings through 30 which said characters are visible, and arms pivotally connected to said cover and to said plate.
2. In a device of the character described, the combination of a plate provided with 35 means for securing it to a board or the like, arms pivoted to swing to and from said plate, cross bars carried by said arms, rings carried by said cross bars, said plate having recesses to receive said rings, sheets exhibiting 40 characters revoluble on said rings, a cover for said sheets having openings through which said characters are visible, and arms pivotally connected to said cover and to said plate.
- 45 3. In a device of the character described, the combination of a plate provided with means for securing it to a board or the like, arms pivoted to swing to and from said plate, cross bars carried by said arms, rings 50 carried by said cross bars and having flanges, sheets exhibiting characters having recesses engaging said rings and flanges, a cover for said sheets having openings through which said characters are visible, and arms pivot- 55 ally connected to said cover and to said plate.
4. In a device of the character described, the combination of a plate provided with means for securing it to a board or the like,

arms pivoted to swing to and from said 60 plate, cross bars carried by said arms, each comprising two longitudinally divided sections, rings having flanges and carried by said cross bars and also divided, part being contained on each bar section, sheets exhibiting characters having recesses engaging 65 said rings and flanges, a cover for said sheets having openings through which said characters are visible, and arms pivotally connected to said cover and to said plate. 70

5. In a device of the character described, the combination of a plate provided with means for securing it to a board or the like, 75 arms pivoted to swing to and from said plate, cross bars carried by said arms, rings carried by said cross bars, sheets exhibiting characters revoluble on said rings, a cover for said sheets having openings through which said characters are visible, arms pivotally connected to said cover and to said 80 plate, latches movably secured on the back of said plate, and lips on the under side of said cover engaged by said latches.

6. In a device of the character described, the combination of a plate provided with 85 means for securing it to a board or the like, arms pivoted to swing to and from said plate, cross bars carried by said arms, rings carried by said cross bars, sheets exhibiting characters revoluble on said rings, a cover 90 for said sheets having openings through which said characters are visible, arms pivotally connected to said cover and to said plate, latches secured movably in unison on the back of said plate, one of said latches 95 having a part adapted to be moved by a thin blade inserted between said cover and the board upon which the plate is secured, and lips on the under side of said cover engaged by said latches. 100

7. In a device of the character described, the combination of a plate provided with means for securing it to a board or the like, arms pivoted to swing to and from 105 said plate, cross bars carried by said arms, rings carried by said cross bars, sheets exhibiting characters revoluble on said rings, a cover for said sheets having openings through which said characters are visible, arms pivotally connected to said cover and to said plate, latches secured movably in unison on the back of said plate, a spring for operatively moving said latches, and lips on the under side of said cover engaged by said latches. 110
